J. F. MINCHER

VULCANIZING APPARATUS

Filed Aug. 21, 1922

JOSEPH F. MINCHER
INVENTOR

BY *Hadley Freeman*
ATTORNEY

UNITED STATES PATENT OFFICE.

JOSEPH F. MINCHER, OF MILWAUKEE, WISCONSIN, ASSIGNOR TO THE FISK RUBBER COMPANY, OF CHICOPEE FALLS, MASSACHUSETTS, A CORPORATION OF MASSACHUSETTS.

VULCANIZING APPARATUS.

Application filed August 21, 1922. Serial No. 583,399.

In curing inner tubes on a circular mandrel it has been customary to support the mandrel from one or both of the ends in such manner that the ends are at the top of 5 the annulus. I find that with the mandrel thus supported the condensation within the mandrel collects at the lowest point and retards the cure of the tube at that point and I accordingly prefer to suspend the mandrel 10 in such a manner that the free ends thereof are at substantially the lowest point of the annulus. In the drawings accompanying this specification and forming a part thereof I have shown, for purposes of illustration, 15 one form which my invention may assume.

In these drawings:

Figure 1 shows a mandrel supported in accordance with this illustrative embodiment, while 20 Figure 2 shows in more detail the connection between the mandrel support and the mandrel.

In the drawings I have shown a mandrel 10 closed at one end 11 by a plug 12 having 25 a rectangular aperture 13 adapted to receive the correspondingly shaped end 14 of a hanger 15 which is provided with an offset 16 adapted to clear the upper portion of the mandrel 10. This hanger 15 may be supported in any suitable manner as by a bracket 17 secured to the upper end of the offset 16 and carrying a pulley 18 adapted to ride on a track 19. The other end 20 of the mandrel 10 may be left freely open to 30 permit condensation to escape and if desired an aperture 21 may be formed in the plug 12 for the same purpose and also to permit free circulation of steam through the mandrel during curing. To facilitate applying the tube to the mandrel and stripping the tube from the mandrel, the aperture 13, and 35 also the aperture 21 if present, may be plugged during these operations. Inasmuch, however, as the tube ordinarily does

not come to the ends of the mandrel 10 the usual amount of condensation, even if retained in the ends 11 and 20, will not cool the mandrel over any portion of the area covered by the tube and therefore will have no appreciable effect on the vulcanization of 50 the tube.

While I have illustrated herein one form which my invention may assume this disclosure is illustrative only and my invention is not limited thereto.

55

I claim:

1. Means for supporting a circular mandrel comprising a hanger adapted to engage one end of the mandrel and extended beyond and across the mandrel circumference to permit free suspension of the mandrel. 60

2. Means for supporting a circular mandrel comprising a hanger adapted to non-rotatably engage one end of the mandrel and extended diametrically across and beyond the circumference of the mandrel to permit free suspension thereof. 65

3. Means for supporting a circular mandrel comprising a hanger adapted to non-rotatably engage one end of the mandrel and extended across and beyond the circumference of the mandrel to permit free suspension thereof. 70

4. Means for supporting a circular mandrel comprising a hanger adapted to engage one end of the mandrel and provided with an offset to encircle the mandrel at a point remote from this point of engagement therewith. 75

5. Means for supporting a circular mandrel comprising a hanger adapted to be removably secured to one end of the mandrel and extended across and beyond the circumference of the mandrel to permit free suspension thereof. 80

In testimony whereof I have signed my name to the above specification.

JOSEPH F. MINCHER
